CLAMP FOR TAKING UP SLACK IN ROPES
OR THE LIKE

John F. Grayson, 2968 Redwood St., San Diego, Calif.

Filed June 17, 1963, Ser. No. 75,355

Term of patent 7 years

(Cl. D54—11)

Fig. 1.Fig. 2.Fig. 3.FIG. 1 is a side elevation of one side of the clamp for taking up slack in ropes or the like.

FIG. 2 is an elevation of the side of the clamp opposite to that shown in FIG. 1.

FIG. 3 is an end view of the clamp, showing the same as it appears when the observer is viewing either end thereof.

I claim:

The ornamental design for a clamp for taking up slack in ropes or the like, as shown and described.
